FIG. 1 is a side elevational view of a unit for dispensing liquid from a container showing our new design;

FIG. 2 is a side elevational view showing the side opposite that seen in FIG. 1;

FIG. 3 is a top plan view;

FIG. 4 is a bottom plan view;

FIG. 5 is a rear elevational view; and

FIG. 6 is a front elevational view thereof.

The broken line showing a portion of a container in FIG. 1 is for illustrative purposes only.

This is a continuation in part of our earlier application Ser. No. D. 10,963, filed Mar. 13, 1968 and now abandoned.

We claim:

The ornamental design for a unit for dispensing liquid from a container, as shown and described.
